UNITED STATES PATENT OFFICE.

WILLIAM S. HAMM, OF CHICAGO, ILLINOIS, ASSIGNOR TO THE ADAMS & WESTLAKE COMPANY, A CORPORATION OF ILLINOIS.

GAS-LAMP.

SPECIFICATION forming part of Letters Patent No. 690,276, dated December 31, 1901.

Application filed July 24, 1901. Serial No. 69,503. (No model.)

To all whom it may concern:

Be it known that I, WILLIAM S. HAMM, a citizen of the United States, and a resident of Chicago, county of Cook, and State of Illinois, have invented certain new and useful improvements in Gas-Lamps, of which the following is a specification, and which are illustrated in the accompanying drawings, forming a part thereof.

10 This invention relates to lamps, and has particular reference to that class employed for illuminating railway-cars or other vehicles, although it will be readily understood that its use is not restricted thereto and that 15 it may be adapted to any situation where conditions favorable to its utilization exist.

The object of the invention is to provide in a lamp of the character referred to for securing a free circulation of air about the gas-supply pipe and for preventing the heating of the 20 gas before consumption by the heat generated by the burning gas, it being well known that certain gases, such as acetylene, require to be kept cool in order that the illuminating 25 efficiency thereof may not be impaired.

The invention consists generally of a plurality of flame-chambers arranged in a cluster, a smoke-flue leading from each chamber and discharging through the ceiling to which 30 the lamp is applied or into a common flue, and means for conducting the gas to the several flame-chambers through the space intermediate of such chambers and the smoke-flues.

The invention is fully illustrated in the accompanying drawings, in which—

35 Figure 1 is a central vertical section of the lamp, showing the manner of securing the same to a car-ceiling or other support and some of the parts being shown in full lines; 40 and Fig. 2 is a section on the line 22 of Fig. 1.

The central gas-supply pipe 10 is provided at its lower end with a plurality of radiating branches 11, suitable means, such as the upwardly-curved bracket-arms 12, radiating 45 from the upper end of the supply-pipe, threaded bolts 13, projecting upwardly from the bracket-arms 12, and nuts 14 for retaining the bolts, being employed for securing the lamp to the ceiling 15 of a car or other 50 chamber. Each of the branches 11 has a gas-key 16 and terminates in a burner 17, inclosed

in a flame-chamber—in the present instance a globe 18—from which leads upwardly a smoke-flue 19, the several flues 19 being inclined inwardly, and, passing through the ceiling of 55 the car, discharge above the upper end of the supply-pipe 10 and into a common centrally-located flue 20, which projects through the upper car-deck 15^a.

The flues 19 may be of continuous tubing, 60 or, as illustrated in Fig. 1, tubes 21, interposed between the ends of the flues 19 and the flue 20, may be provided, and the said tubes 21 pass between adjacent pairs of the bracket-arms 12, as clearly shown in Fig. 2. 65

As will be observed, the supply-pipe 10 is disposed centrally with relation to the surrounding smoke-flues 19 and is suitably spaced therefrom, so as to permit of a free circulation of air around the gas-pipe, and is preferably located within a tube 22, which serves as well to shield the same from the heat radiating from the surrounding smoke-flues as to add to the ornamentation of the lamp. 70

The upper ends of the flues 19, or, as in the 75 construction illustrated, the tubes 21, may be inclosed in a casing 23, which is preferably made of metal and in the form of a bowl, the rim thereof abutting against the ceiling of the car or other chamber within which the lamp 80 may be located. The flues 19 are then supported by the casing 23, which latter is provided with nipples 24 to receive the ends of the tubes 21.

The casing 23 is freely perforated at the 85 sides, as at 25, to provide for an uninterrupted circulation of air therethrough and around the upper end of the supply-pipe 10, extending therein, and communication with the outer atmosphere is established by means of a tube 90 26, surrounding the flue 20 and passing through the ceiling and upper deck of the car.

Air for supporting combustion within the flame-chambers may be supplied in the usual manner—that is to say, through apertures in 95 the globe-supporting disks—and air may also enter between the upper ends of the globes and the corrugated bottoms of the smoke-bells.

One of the bolts for securing the lamp to 100 the car-deck or other support and its companion bracket-arm may be provided with a

passage 27 for conducting the gas from the service-pipe (not shown) to the lamp-supply pipe 10.

In the drawings I have illustrated a lamp 5 or chandelier with four sets of flame-chambers and smoke-flues; but it will be obvious that the number is immaterial and may be varied as desired. The construction shown and described provides for a depending gas- 10 supply pipe surrounded by but spaced from independent smoke-flues leading from the flame-chambers, so that it is free from the influence of the heat radiating from the smoke-flues and ascending from the flame-chambers, 15 and for thorough circulation of the air around the gas-pipe, whereby the gas is kept cool, so as to permit the best results to be obtained therefrom in its illuminating power and to prevent it from gumming up the pipes.

20 I claim as my invention—

1. In a deck or ceiling gas-lamp, in combination, a plurality of flame-chambers arranged in a cluster, a smoke-flue leading from each chamber, and means for leading 25 gas to the several flame-chambers through the space intermediate of such chambers, the said conveying means being entirely outside of and spaced apart from the flues.

2. In a deck or ceiling gas-lamp, in combination, a plurality of flame-chambers arranged in a cluster, a flue leading through the ceiling to which the lamp is applied, a smoke-flue leading from each flame-chamber and discharging into the first-mentioned flue, and 35 a gas-pipe communicating with the several flame-chambers and being wholly outside of the smoke-flues.

3. In a gas-lamp, in combination, a plurality of flame-chambers arranged in a cluster, 40 a supply-pipe, branches for conducting gas to the flame-chambers, a smoke-flue leading from each chamber and spaced from the supply-pipe, and a common flue located above the supply-pipe and into which the several 45 smoke-flues discharge.

4. In a gas-lamp, in combination, a plurality of flame-chambers arranged in a cluster, a supply-pipe, branches for conducting gas to the flame-chambers, upwardly-extending 50 bracket-arms radiating from the supply-pipe for securing the lamp to a support, a flue located above the supply-pipe, and a smoke-flue for each chamber passing between adjacent pairs of bracket-arms and discharging 55 into the flue.

5. In a gas-lamp, in combination, a plurality of flame-chambers, a supply-pipe, branches for conducting gas to the flame-chambers,

radial bracket-arms extending upwardly from the upper end of the supply-pipe, bolts projecting from the bracket-arms, and nuts for securing the bolts to a support, one of the said bolts and its companion bracket-arm having a passage for leading the gas to the supply-pipe.

6. In a gas-lamp, in combination, a plurality of flame-chambers arranged in a cluster, a supply-pipe, branches for conducting gas to the flame-chambers, smoke-flues leading from the flame-chambers and spaced from 70 and about the supply-pipe, a common flue located above the supply-pipe and into which the smoke-flues discharge, bracket-arms radiating from the upper end of the supply-pipe and provided with bolts extending upwardly 75 and at the sides of the smoke-flues, and nuts for securing the bolts to a support, and one of the said bolts and its companion bracket-arms having a passage for leading the gas to the supply-pipe.

7. In a gas-lamp, in combination, a central depending supply-pipe, a plurality of flame-chambers arranged in a cluster, branches radiating from the supply-pipe and conducting gas to the flame-chambers, and an independent smoke-flue leading upwardly and inwardly from each flame-chamber, the several flues being spaced from and about the supply-pipe and discharging above the upper end of the same.

8. In a deck or ceiling lamp, in combination, a plurality of flame-chambers arranged in a cluster, a smoke-flue leading from each of such chambers through the ceiling to which the lamp is applied, and a gas-pipe leading to 95 each flame-chamber, and being entirely outside of and spaced apart from the flues.

9. In a deck or ceiling lamp, in combination, a plurality of flame-chambers arranged in a cluster, a smoke-flue leading from each 100 of such chambers through the ceiling to which the lamp is applied, and a gas-pipe leading to each flame-chamber, and being entirely outside of the flues.

10. In a gas-lamp, in combination, a plurality of flame-chambers, a supply-pipe, branches leading to the flame-chambers, and an independent flue leading upwardly from each flame-chamber, the several flues being spaced from and about the supply-pipe and discharging 110 above the upper end of the same.

WILLIAM S. HAMM.
